UNITED STATES PATENT OFFICE

150,011

DESIGN FOR A NOISEMAKING AIRPLANE TOY

John Guariglia, Benicia, Calif.

Application February 18, 1947, Serial No. 136,974

Term of patent 14 years

(Cl. D34—15)

To all whom it may concern:

Be it known that I, John Guariglia, a citizen of the United States, residing at Benicia, in the county of Solano and State of California, have invented a new, original, and ornamental Design for a Noisemaking Airplane Toy, of which the following is a specification, reference being had to the accompanying drawing, forming a part thereof.

Figure 1 is a front view of a noisemaking airplane toy showing my new design.

Figure 2 is a side view.

Figure 3 is a top plan view.

I claim:

The ornamental design for a noisemaking airplane toy, as shown.

JOHN GUARIGLIA.
